UNITED STATES PATENT OFFICE.

PIERRE CHOUTEAU, OF ST. LOUIS, MISSOURI.

DESIGN FOR A PISTOL-GRIP ENGINE.

SPECIFICATION forming part of Design No. 23,679, dated October 2, 1894.

Application filed March 13, 1894. Serial No. 503,513. Term of patent 14 years.

To all whom it may concern:

Be it known that I, PIERRE CHOUTEAU, a citizen of the United States, residing at the city of St. Louis, State of Missouri, have invented a certain new and original Design for Pistol-Grip Engines, of which the following is a full, clear, and exact description, reference being had to the accompanying drawing, forming a part of this specification, wherein the figure represents a side elevational view of the pistol-grip engine ornamented and configured according to my new design.

The design of pistol-grip engine which forms the subject-matter of this application, being so termed by reason of the resemblance between its handle and the stock of a pistol, is adapted to be used in conjunction with tools, such as chisels, &c., which are inserted in the chuck or tool-holder in its forward end, said tool being acted upon by the piston which delivers an impacting blow thereupon. The tool is guided in its work by the pistol-grip handle, and is used in stone cutting, carving, and chipping, boiler-calking, and various other work requiring implements of this character. Motive fluid is supplied to the engine from a suitable source of supply, through the medium of a flexible pipe-hose, which is attached to the nipple D.

In the drawing, A indicates the cylinder ornamented about the middle of its body-portion with a bead a. From the front end of

this cylinder, projects a chuck or tool-holder B, which is ornamented on its forward end 35 with a fluted bead b, of milling or knurled work.

C is a cap or cylinder-head in the form of a handle-base, which is larger than the cylinder A and forms a shoulder c in conjunction 40 therewith.

Extending transversely to the cap or cylinder-head C, is a semi-cylindrical projection, the lower end of which terminates in a cylindrical projection D, which is threaded. The 45 opposite end of this semi-cylindrical projection extends rearwardly and outwardly at about right angles in the form of a pistol-handle. Extending upwardly and outwardly from the upper curved portion of this pistol- 50 handle, is a flattened, horn-like projection E.

At the junction of the pistol-handle and handle-base or cap C, as I have termed it, is a boss, from which extends a trigger F, flattened somewhat at its outer end, said outer 55 end being curved outwardly and upwardly.

What I claim is—

The design for a pistol-grip engine substantially as herein shown and described.

In testimony whereof I have hereunto affixed my signature, in the presence of two witnesses, this 10th day of March, 1894.

PIERRE CHOUTEAU.
